SERVOMOTOR

George A. Waldie, Miamisburg, Ohio, assignor to
 The Hydraulic Development Corp., Inc., Wil-
 mington, Del., a corporation of Delaware

Application October 6, 1941, Serial No. 413,771

12 Claims. (Cl. 121—41)

This invention relates to control means and, in particular, to fluid operable servomotor means for controlling a reciprocable element.

It is an object of the invention to provide a simplified fluid pressure control mechanism for controlling the position of a reciprocable member.

It is another object of the invention to provide a control mechanism which, responsive to different fluid pressures, is adapted to hold a reciprocable element in a predetermined position or to move it away from the said position.

A further object of the invention consists in the provision of a fluid operable servomotor which may be used in connection with variable delivery pumps for controlling the same.

It is still another object to provide a fluid operable servomotor for variable delivery pumps which heretofore required the use of a plurality of servomotors.

A still further object of the invention consists in the provision of a fluid operable servomotor for variable delivery pumps which is universal in use inasmuch as it is adapted not only to put such pumps on stroke but also to vary the delivery thereof in response to predetermined pressures.

These and other objects and advantages of the invention will appear more clearly from the following specification in connection with the accompanying drawings, in which:

Figure 1 diagrammatically illustrates a hydraulic open press circuit comprising a vane pump with a servomotor according to the invention.

Figure 2 is a longitudinal section through the servomotor shown in Figure 1.

Figures 3 and 4 illustrate the servomotor of Figure 2 in working position, and pressure-holding position respectively.

Figure 5 illustrates a hydraulic open press circuit comprising a radial piston pump with a servomotor according to the invention.

Figure 6 is a diagrammatic illustration of a closed hydraulic press circuit comprising a vane pump which is associated with a servomotor according to the invention.

Figure 7 shows, in section, a portion of the vane pump as may be used in the circuits shown in the drawings.

Figure 8 is a diagrammatic illustration of a radial piston pump as may be used in connection with the circuit of Figure 5.

Figure 9 is a diagrammatic illustration of a closed press circuit comprising a vane pump with two servomotors according to the invention for varying the delivery as well as the direction of the vane pump.

Figure 10 shows, in section, the servomotors used in connection with Figure 9.

Figure 11 is a choker check valve which may be used in the circuit of Figure 9.

General construction

The servomotor according to the invention substantially comprises a thrust rod with intake and discharge ports, which has reciprocably mounted therein a servo-valve spool. The servo-valve spool has a piston-like extension reciprocable in a correspondingly shaped cylinder in the thrust rod which is in constant hydraulic communication with the inlet port, while conduit means associated with the servo-valve spool are adapted to connect the piston area on the thrust rod selectively with the inlet port or with the discharge port. A spring, preferably adjustable, is interposed between the thrust rod and the servo-valve spool so as continuously to urge the valve spool and the thrust rod into engagement with each other.

The supply of pressure fluid to the inlet port normally brings the thrust rod into or holds the same in engagement with a reciprocable member to be controlled, for instance, the flow-control member of a variable delivery pump. When the pressure at the inlet port reaches a predetermined value, it acts upon the piston-like extension of the servo-valve spool so as to cause the same to release fluid from the piston area of the thrust rod to the discharge port, whereupon the thrust rod varies its position to allow variation of the position of the member to be controlled. When the pressure at the inlet port again drops, the spring interposed between the servo-valve spool and the thrust rod moves the valve spool into its initial position, thereby enabling pressure fluid passing through the inlet port to shift the thrust rod to its previous position.

Structural arrangement

Referring now to the drawings in detail, the circuit shown in Figure 1 comprises a vane pump 1 with a cylinder block 2 (see Figure 7), adapted to be moved into a position eccentric to the rotor 3 which has a plurality of vanes 4 reciprocable in cylinders 5, and having their ends in engagement with the cylinder wall 6. The cylinder block 2 has a fluid inlet 7 and a fluid outlet 8. The fluid outlet 8 of the vane pump 1 is connected to a conduit 9 (Figure 1) which leads to a four-way valve 10 of any desired type which in its turn is connected with two conduits 11 and 12 respectively leading to the upper and lower portion of a cylinder 13 having reciprocably mounted therein

a piston 14. Also connected with the four-way valve 10 is a conduit 15 leading to a fluid tank 16. The tank 16 is connected with a conduit 17 leading to the fluid inlet 7 of the vane pump 1.

Branching off from the conduit 9 is a conduit 18 leading to the inlet port 19 of the servomotor, generally designated 20, and connected in any desired manner, for instance by screws 21, with the casing of the pump 1.

The servomotor 20 comprises a cylinder 22 with a cylinder bore 23 having a shoulder 24. Reciprocably mounted in the cylinder bore 23 is a cylindrical portion 25 of the thrust rod 26. The thrust rod 26 has an extension 27 passing through the pump casing and adapted to engage the cylinder block 2.

Interposed between the pump casing and the cylinder block 2 is a weak spring 28 which is just strong enough to shift the cylinder block 2 into position eccentric to the rotor 3. It should, however, be noted that when the vane pump 1 is delivering pressure fluid so that the well known reaction, inherent to vane pumps, occurs, the spring 28 is not strong enough to oppose said reaction, thereby allowing the cylinder block 2 to move against the thrust of the spring 28.

The thrust rod portion 25 is provided with two annular grooves 29 and 30 respectively, of which the groove 29 is adapted to communicate with the inlet port 19 and, furthermore, is in continuous hydraulic connection with the passageway 31. The passageway 31 communicates through ducts 32 and 33 with the end of a small cylinder 34 provided in the extension 27 and having slidably mounted therein a piston 35 connected to a servo-valve spool, generally designated 36. The servo-valve spool 36 has an annular groove 37 adapted to effect hydraulic communication between the passageway 31 and a passageway 38 leading to the left end portion of the cylinder bore 23. The thrust rod 26 is provided with an annular groove 39 communicating through a passageway 40 with the cylinder bore 41 in the thrust rod 26. The servo-valve spool 36 is slidably mounted in the bore 41 and is also adapted, by means of the annular groove 37, to effect hydraulic communication between the passageway 38 and the passageway 40 which in its turn is adapted, through groove 39, to communicate with the discharge port 42 in the servomotor 20. The length of the annular groove 37 is preferably, although not necessarily, so dimensioned that it equals the shortest distance between the passageways 31 and 40.

As will be seen from Figure 2, the thrust rod extension 27 is provided at its left end with a shoulder 43 for abutment with the valve spool 36 so that when the valve spool 36 and the extension 27 engage each other an annular cylindrical space 44 remains. The space 44 communicates with a duct 45 leading to the annular groove 30 which is adapted to communicate through duct 46 with a port 47. The port 47 may be connected to a fluid source but in the example of Figure 2 is closed by a plug 48.

Mounted within the valve spool 36 is a spring 49, one end of which engages the valve spool 36, whereas the other end of spring 49 abuts a thrust nut 50. The thrust nut 50 is provided with wings 51 passing through slots 52 in the thrust rod 26 and slidably mounted in longitudinal grooves 53 provided in the servomotor casing 54. The thrust nut 50 is provided with an inner thread engaging a threaded portion 55 of a control stem 56 which is rotatable by the knob 57 connected

thereto. The knob 57 engages a thrust washer 58 threadedly engaging the left end portion of the thrust rod 26 which also threadedly engages a volume limiting knob 59 adapted to vary the possible stroke of the thrust rod 26. Interposed between the thrust washer and the collar 60 is a thrust bearing 61.

The structure shown in Figures 1 and 2 operates as follows:

Supposing that the pump 1 is running and that the four-way valve 10 occupies its neutral or bypass position, fluid delivered by pump 1 will pass through conduit 9, four-way valve 10, conduit 15, tank 16, and from there through conduit 17 back to the pump 1. During this time the spring 28 maintains the cylinder block 2 of pump 1 in its eccentric position relative to the pump rotor 3 and the elements of the servomotor 20 occupy the position shown in Figure 3.

If, now, the four-way valve 10 is shifted to its working position for forward movement of the piston 14, fluid delivered by the pump 1 will pass through conduit 9, four-way valve 10 and conduit 11 into the upper portion of the cylinder 13, while fluid expelled from cylinder 13 will pass through conduit 12, four-way valve 10 and conduit 15 into tank 16.

As soon as the piston 14 encounters resistance exerted by a work piece, pressure begins to build up in conduits 11 and 9, and this pressure is conveyed through conduit 18, port 19 and passageway 31 through the annular groove 37 and passageway 38 to the cylinder bore 23 adjacent the shoulder 24. Here it acts upon the piston area 62 of the thrust rod 26 so as to cause the latter positively to engage the cylinder block 2 and to support the action of the spring 28 against the reaction now occurring in the vane pump 1 and tending to move the cylinder block 2 into position concentric with the pump rotor 3. Simultaneously, the pressure prevailing in conduit 18 is conveyed through port 19, passageway 31, ducts 32 and 33 to the cylinder 34 where it acts upon the piston 35 without, however, moving the valve spool 36. The servomotor 20 now occupies the working position illustrated in Figure 3.

As soon as a predetermined pressure has been built up in the upper portion of the cylinder 13 and, thereby, also in conduits 11, 9 and 18, this pressure will overcome the thrust of spring 49 and, acting upon the piston 35, will move the valve spool 36 toward the left, closing the passageway 31 and establishing hydraulic communication between the passageways 38 and 40 and the discharge port 42. The pressure fluid acting upon the piston area 62 is, therefore, discharged and further pressure acting upon piston 35 moves the valve spool 36 together with the thrust rod 26 toward the left with regard to Figure 2. The cylinder block 2 immediately follows up the leftward movement of the thrust rod 26 due to the reaction occurring in the vane pump 1. The elements of the servomotor 20 then come to a halt when equilibrium is again established and occupy the pressure-holding position shown in Figure 4.

If, for some reason, the pressure acting upon piston 14 and prevailing in conduits 11, 9 and 18 should drop, a corresponding drop in pressure will also occur in cylinder 34 so that the valve spool 36 is moved toward the right by spring 49. This movement causes hydraulic communication again between passageway 31 and passageway 38 so that pressure fluid is conveyed from conduit 18 to the piston area 62, thereby causing rightward movement of the thrust rod 26.

If it is desired to retract the piston 14, the four-way valve 10 is shifted into retraction stroke position so that pressure fluid delivered by the pump 1 passes through conduit 9, four-way valve 10 and conduit 12 to the lower part of the cylinder 13, while fluid expelled from the upper part of cylinder 13 passes through conduit 11, four-way valve 10, and conduit 15 into the tank 16. Otherwise, the operation of the servomotor 20 will be the same as described in connection with the forward stroke of piston 14.

The possibility of using a servomotor according to the invention in an open hydraulic system powered by radial pump or any shiftable pump in which no internal reactive force, as occurs in a vane pump, can be utilized is illustrated in Figure 5. The circuit shown in this figure is the same open circuit shown in Figure 1. The only difference between the two is the addition of a fluid pressure responsive piston 63 reciprocable in a cylinder 64 associated with the radial pump 65. The piston 63, when acted upon by fluid pressure, urges the flow-control member or shift ring (not shown) of the radial pump 65 into position concentric to the rotor of the pump 65. Similar parts in the circuit of Figure 5 are, therefore, designated with the same reference numerals as the corresponding parts of Figure 1.

As will be seen from Figure 5, the cylinder 64 is connected through conduit 66 with the pressure line 9. In this way pressure prevailing in conduit 9 will be conveyed through conduit 66 into cylinder 64 where it acts upon piston 63 so as to move the flow-control member or shift ring of pump 65 toward the left with regard to Figure 6; in other words, the fluid pressure acting upon piston 63 tends to move the flow control member of pump 65 into concentric position with regard to the pump rotor. It will, therefore, be clear that the reactive force occurring in the vane pump 1 is replaced in the circuit of Figure 5 by the pressure conveyed through conduits 9 and 66 and acting upon the piston 63. Otherwise, the operation of the circuit in Figure 5 is the same as that described in connection with the circuit shown in Figure 1.

Two possibilities for closed hydraulic circuits are illustrated in Figures 6 and 9.

Referring first to Figure 6, the circuit shown therein comprises a vane pump 67, which may be of any desired type, for instance, correspond to the vane pump 1 in Figure 1, or may be replaced by a radial piston pump comprising a spring within the pressure cylinder at the right side of the pump. The vane pump 67 is of the reversible type and has connected on one side thereof the servomotor 20 as described in detail in connection with Figure 2. On the opposite side of the vane pump 67 is arranged a cylinder 68 having reciprocably mounted therein a fluid pressure responsive piston 69 which is adapted to engage the cylinder block 2 and to move the latter toward the left with regard to Figure 6.

The cylinder 68 is connected to a conduit 70 leading to the four-way valve 10 which in its turn is connected to a conduit 71 comprising a check valve 72 and leading to a conduit 73. The conduit 73 which comprises a choker check valve 74 has one end connected to the inlet port 19 of the servomotor 20, while the other end of the conduit 73 leads to a conduit 75. The choker check valve 74 is preferably of the type shown in Figure 11, with a by-pass channel 74a and a choke 74b. One end of the conduit 75 is connected to the vane pump 67, whereas the other end leads to the up-

per portion of the cylinder 13 having reciprocably mounted therein the piston 14. The piston 14 is connected to a piston rod 76 which carries an arm 77 adapted to engage a collar 78 adjustably mounted on a control rod 79. The upper end of the control rod 79 carries an adjustable arm 81 of a bell crank lever 82, the other arm 83 of which is adapted to engage the knob 57 so as to move through the latter the thrust washer 58 and the thrust rod 26 threadedly connected thereto.

The lower portion of cylinder 13 in Figure 6 communicates with a conduit 84 which leads to the vane pump 67 and communicates through conduit 85 with a make-up or shuttle valve 86 of a well known type. The valve 86 has a conduit 87 communicating with the conduit 75 and has a further conduit 88 leading to the fluid tank 16. Also communicating with the fluid tank 16 is a conduit 89 leading to the four-way valve 10. Branching off from the conduit 89 is a conduit 90 leading to the suction side of a constant delivery pilot pump 91, the pressure side of which is connected to conduit 92 leading to the four-way valve 10. Branching off from the conduit 92 is a conduit 93 which comprises a relief valve 94 and leads to the conduit 89.

The operation of the system shown in Figure 6 is as follows:

Supposing that the pumps 91 and 67 are running but that pump 67 is in neutral or no delivery position, and that it is now desired to effect a forward stroke of the piston 14. To this end the four-way valve 10 is moved into forward stroke position so that hydraulic communication is established between the conduits 92 and 71. Pilot pressure is then directed to the port 19 and immediately transmitted to the piston area 62, thereby causing the thrust rod 26 to put the pump 67 into forward stroke position. This movement of the thrust rod 26 is also transmitted to the valve spool 36 by the spring 49 so that the valve spool 36 immediately follows up the movement of the thrust rod 26. The pump 67 then begins to deliver pressure fluid through conduit 75 into the upper portion of the cylinder 13.

It should be noted that the pump 91 is adapted merely to create sufficient pressure to move the thrust rod 26 for causing the latter to put the pump on stroke, but is not adapted to create such a pressure as to cause the valve spool 36 to move against the thrust of spring 49.

If the pump 91 has reached the pressure required for the above referred to shifting movement of the thrust rod 26, any excessive pressure delivered by the pump 91 is released through relief valve 94 into the tank 16. As soon as pressure builds up in the upper portion of the cylinder 13, this pressure is conveyed through conduit 73 to port 19, and from there to the piston area 62 so as to positively maintain the thrust rod 26 in engagement with the cylinder block 2 as long as the pressure in the upper portion of cylinder 13 does not exceed a predetermined value. At this time the check valve 72 closes, whereas the choker check valve 74 is open.

When a predetermined pressure has been built up in the upper portion of cylinder 13, for instance at the end of the stroke of piston 14, this pressure is conveyed through conduits 75 and 73, port 19 and ducts 32 and 33 to cylinder 34 where it acts upon the piston 35 as described in connection with Figure 2 so as to move the valve spool 36 toward the left. As a result, the thrust rod 26 likewise moves toward the left, as previously described, and the reaction in the vane

pump 67 causes movement of the latter toward neutral or substantially no delivery position.

When it is desired to reverse the movement of the piston 14, the four-way valve 10 is shifted so as to establish hydraulic communication between the conduits 92 and 70. Pressure fluid delivered by the pilot pump 91 then acts upon the piston 69 which shifts the cylinder block 2 to the left across the center and holds it there against the pump reaction which is relatively low under pull-back pressure. Fluid trapped by the piston 35 bleeds off during the reverse stroke of piston 14 by passing out through the channel 74a of the choker check valve 74 in conduit 73. Finally, when the piston 14 has reached the end of its retraction stroke, the arm 71 engages the collar 78, thereby lifting the control rod 79, which latter, through arm 80, acts upon the bell crank lever 82 which in its turn forces the thrust rod 26 through knob 57 and thrust washer 58 to neutral position against the pilot pressure.

As mentioned above, the vane pump 67 of Figure 6 may, if desired, be replaced by a reversible radial piston pump. In this instance the only alteration necessary consists in the addition of a light spring behind the piston 68 which is adapted to exert a force just sufficient to cause follow-up of the flow-control member or shift ring of the radial piston pump in the pressure-holding period to move the pump to neutral position when the thrust rod 26 moves toward the left with regard to Figure 2.

Referring now to Figure 9, this figure illustrates a further possibility for closed hydraulic systems, namely, pressure control for either forward or reverse delivery of a reversible pump by the use of two of the control units shown in Figure 2, of which one is to be arranged on each side of the pump. The primary object of such an arrangement is to provide pressure control on both strokes of the press, for example, in connection with reciprocating machine drives, or in connection with injection presses where knockout pressures are not controllable at present.

Another object of the arrangement shown in Figure 9 is to provide for moving the pump to idling position under low pressure at the end of a cycle.

As will be seen from the drawings, the hydraulic circuit of Figure 9 resembles that of Figure 6, a pilot pump 95 being employed to move the main pump 96 off center in either direction through the setting of the four-way valve 10, and the main pump pressure being adapted, through a choker check valve hook-up 74, to supersede pilot pressure in holding the pump on stroke and in providing pressure control. The difference between the arrangement of Figures 9 and 10 on one hand and the circuit of Figure 6 lies in the use of the annular cylindrical space 44 for nullifying the effect of the control unit.

As will be noted from Figure 9, the pilot line 97 leading to the port 19 of the servomotor 20 communicates through conduit 98 with the port 47a of the servomotor 20a, which in its construction completely corresponds to the servomotor 20 so that corresponding elements are designated with the same reference numerals, however, with the additional letter *a*. Similarly, the pilot line 99 leading to the port 19a of servomotor 20a communicates through conduit 100 with the port 47 of the servomotor 20. Otherwise, the circuit of Figure 9 substantially corresponds to that of Figure 6.

To effect a working cycle of piston 14 in the

circuit of Figure 9, the pumps 95 and 96 are started. The operator then shifts the four-way valve 10 so as to establish hydraulic connection between conduits 92 and 91, thereby admitting pilot pressure to the port 19 and to the piston area 62, previously described in connection with Figures 2 and 6. As a result, the thrust rod 26 puts the pump 96 on forward stroke. Simultaneously with the admittance of fluid pressure to the piston area 62, pilot pressure also is admitted into the space 44a which causes the valve spool 36a to move toward the right and to establish hydraulic connection between the piston area 62a and the discharge port 42a which is connected with the tank 16. The exhaust of fluid from the piston area 62a allows the cylinder block 2 to move the thrust rod 26a toward the right. The relative positions of the servomotors 20 and 20a are then as illustrated in Figure 10.

As soon as the pump 96 starts to build up pressure in the cylinder 13, the pressure fluid in the pressure line 75 supersedes the pilot pressure in line 97 in the same manner as previously described in connection with Figure 6, while the check valve 72 closes and the delivery of the pilot pump 95 is by-passed to the tank 16 through conduit 93 and relief valve 94. When a predetermined pressure has been established in the upper portion of cylinder 13, for instance at the end of the forward stroke of piston 14, this pressure is conveyed through conduits 75 and 73 to port 19 and from there, in the manner previously described, through cylinder 34 where it acts upon the piston 35 and moves the thrust rod 26 toward the left, so that the reactive force in pump 96 may bring about movement of the cylinder block 2 to neutral position.

If, now, a retraction stroke of the piston 14 is desired, the four-way valve 10 is shifted so as to establish hydraulic connection between the conduits 92, 100 and 99, as previously described in connection with the servomotor 20 of Figure 10. This will result in a leftward movement of the thrust rod 26a so as to put the pump 96 on retraction stroke. Pressure fluid from pump 96 is then conveyed to the lower part of cylinder 13. When the piston 14 has reached the end of its retraction stroke, or if for any other reason a predetermined pressure has been established in the lower part of cylinder 13 according to the setting of spring 49a, this pressure is conveyed through port 19a into cylinder 34a and causes the valve spool 36a to move toward the right, thereby enabling the reactive force in the vane pump 96 to move the latter to neutral or substantially no delivery position.

It should be noted that while the four-way valve 10 is shifted from forward stroke to reverse stroke position, pilot pressure enters the space 44, maintaining the control spring 49 in compressed condition, while pilot pressure is exhausted from the space 44a. Pressure does not instantly pass from the port 19a to the piston area 62a, a slight lapse of time occurring while fluid is leaving the space 44a and spring 49a is pushing the valve spool 36a toward the left. After that, another slight lapse occurs, while the thrust rod 26a is moved to absorb the space previously prevailing between the thrust rod and the cylinder block 2. When contact is made between the cylinder block 2 and the thrust rod 26a, the shifting of the pump from neutral to reverse is effected. In this way, a smooth shifting movement from forward to reverse stroke is effected. On the other hand, during the last

motion movements of the servomotor 20a, nothing can happen within the servomotor 20 which would move the pump to forward stroke position.

If, instead of the vane pump 96, a radial piston pump is used, the reactive force in the vane pump 96 will be replaced by centering springs in the radial piston pump, which centering springs act upon the flow-control member or shift ring of the pump and tend to hold said flow-control member or shift ring in neutral position.

While the servomotor of the present invention has been described in connection with variable delivery pumps, it is, of course, understood that it may also be used for the control of other reciprocable elements.

It will be understood that I desire to comprehend within my invention such modifications as come within the scope of the claims.

Having thus fully described my invention, what I claim as new and desire to secure by Letters Patent is:

1. In combination in a control mechanism, a casing having an inlet port and an outlet port, a fluid operable element reciprocably mounted in said casing, fluid operable control means for controlling the admittance of pressure fluid to an effective area of said reciprocable element, yielding means continuously urging said control means into position for establishing fluid connection between said inlet port and said effective area to cause movement of said fluid operable element into a first predetermined position in response to a first pressure at said inlet port, restricted conduit means connecting said inlet port with an effective area of said control means, means responsive to a second fluid pressure acting upon said effective area of said control means and higher than said first pressure for spacing said control means from an adjacent portion of said reciprocable element, and means responsive to said last mentioned spacing movement of said control means for moving said reciprocable element into a second predetermined position.

2. In combination in a servomotor, a casing having a fluid inlet port and a fluid outlet port, a control rod reciprocable in said casing and being provided with passageways adapted to communicate with said inlet and outlet ports, said control rod also being provided with a fluid operable piston portion adapted, in response to a first pressure at said inlet port, to effect movement of said control rod into a predetermined position, a valve member for controlling hydraulic communication between said piston portion and said ports through said passageways, yielding means interposed between said control rod and said valve member for urging said valve member and said control rod into a predetermined relative position, and means associated with said valve member and forming with said control rod a cylinder-piston-assembly hydraulically connected to said inlet port and adapted, in response to a second fluid pressure at said inlet port higher than said first pressure, to move said valve member into position for connecting said piston portion with said outlet port.

3. In combination in a servomotor, a cylinder body having a fluid inlet port and a fluid outlet port, a hollow piston reciprocably mounted in said cylinder body and having passageways adapted to communicate with said ports, said piston comprising a larger cylinder and also comprising a smaller cylinder, conduit means continuously maintaining hydraulic communication

between said smaller cylinder and said inlet port, a control member reciprocably mounted in said larger cylinder and having an extension reciprocable in said smaller cylinder, said control member being operable to selectively effect communication between said inlet or outlet port and said piston, and yielding means for continuously urging said piston and said control member into a predetermined relative position.

4. In combination, a reciprocable element, a casing, a control member reciprocably mounted in said casing for operating said reciprocable element, said control member having a fluid inlet and a fluid outlet port and also being provided with a piston area, a valve member for controlling hydraulic communication between said piston area and said ports, yielding means continuously urging said valve member into abutment with said control member, a fluid operable cylinder-piston-assembly associated with said valve member and said control member and adapted to be supplied with pressure fluid from said inlet port to effect movement of said valve member relative to said control member against the influence of said yielding means, and means for urging said reciprocable element away from said casing.

5. In combination in a control mechanism for controlling the reciprocative movement of a reciprocable member, a casing, a reciprocable element reciprocable in said casing, said reciprocable element having associated therewith a cylinder and a smaller cylinder and being provided with a piston area responsive to a first fluid pressure acting thereon for shifting said reciprocable element into a first predetermined position, a control valve comprising a piston reciprocable in said cylinder and means forming with an adjacent portion of said reciprocable element a fluid operable cylinder-piston-assembly, and means for actuating said cylinder-piston-assembly in response to a second pressure acting therein and being higher than said first pressure for initiating movement of said reciprocable element into a second predetermined position.

6. In combination in a servomotor, a casing having a fluid inlet and a fluid outlet, a reciprocable element movable in said casing and being provided with a fluid operable piston area, said reciprocable element having a larger cylinder and a smaller cylinder portion, a valve member, having associated therewith conduit means and cylindrical portions reciprocably mounted in said larger and said smaller cylinder portions respectively, for controlling fluid connection between said inlet and outlet ports and said piston area, said reciprocable element being movable into a first predetermined position in response to pressure on said piston area and being movable into a second predetermined position in response to a predetermined pressure on the smaller cylindrical portion of said valve member, and yielding means for continuously urging said valve member into abutment with said reciprocable element.

7. In combination in a servomotor, a casing having a fluid inlet port and a fluid outlet port, an actuating member reciprocably mounted in said casing and having a larger cylinder with a piston area on the outside thereof and also having a smaller cylinder, said actuating member also being provided with passageways adapted respectively to communicate with said ports and said piston area, conduit means continuously effecting hydraulic communication between said inlet port and said smaller cylinder, a control member reciprocable in said actuating member and having

a piston reciprocable in said smaller cylinder and a valve member reciprocable in said larger cylinder for controlling hydraulic communication between said piston area and said ports, spring means arranged within said valve member for continuously urging said smaller piston into the said smaller cylinder, means responsive to a first pressure at said inlet port for moving said actuating member into a first predetermined position, means responsive to a second pressure, higher than said first pressure, for moving said valve member against the thrust of said spring means away from said smaller cylinder and means responsive to the last mentioned movement of said valve member for moving said actuating member together with said valve member to a second predetermined position.

8. In combination, a casing having a fluid inlet port and a fluid outlet port, an actuating member reciprocable in said casing and having passageways therein for communication with said ports, said actuating member having a fluid operable piston area and a first element of a cylinder piston-assembly continuously communicating with said inlet port, a valve member associated with said actuating member and having connected thereto a second element cooperating and forming with said first element said cylinder-piston-assembly, said valve member being operable to control hydraulic communication between said piston area and said ports, adjusting means associated with said actuating member for varying the stroke thereof in one direction, and yielding means interposed between said adjusting means and said valve member for continuously urging the latter into abutment with said actuating member.

9. In combination, a casing having a fluid inlet port and a fluid outlet port, an actuating member reciprocable in said casing and having passageways therein for communication with said ports, said actuating member having a fluid operable piston area and a first element forming a part of a cylinder-piston-assembly, conduit means continuously maintaining fluid connection between said cylinder-piston-assembly and said inlet port, a valve member associated with said actuating member and having connected thereto a second element cooperating and forming with said first element said cylinder-piston-assembly, said valve member being operable to control hydraulic communication between said piston area and said ports, spring means within said valve member for continuously urging the latter into abutment with said actuating member, and adjusting means operable from the outside of said casing for adjusting the thrust of said spring means.

10. In combination, in a servomotor, a casing having a fluid inlet port and a fluid outlet port, a control rod reciprocable in said casing and having a fluid operable piston portion, a reciprocable member adapted to be held by said control

rod in a first predetermined position, said control rod being provided with passageways adapted to communicate with said inlet and outlet ports, a valve member for controlling hydraulic communication between said piston portion and said ports, the piston area of said control rod being adapted in response to a first pressure at said inlet port to actuate said control rod for holding said reciprocable member in said first predetermined position, fluid operable means responsive to a second pressure at said inlet port higher than said first pressure for axially spacing said valve member from said control rod, and means responsive to said last mentioned spacing movement of said valve member for moving said reciprocable member into a second predetermined position.

11. In combination with a reciprocable element, a fluid operable cylinder-piston-assembly adapted to actuate said reciprocable element, actuating means for moving said reciprocable element into a first position, first fluid pressure responsive means adapted, in response to a first fluid pressure acting thereupon, to hold said reciprocable element in said first position independently of said actuating means, means associated with said reciprocable element for urging the latter into a second position, second fluid pressure responsive means responsive to a second pressure acting thereupon and being higher than said first pressure for making said first fluid pressure responsive means ineffective to thereby allow said last mentioned means associated with said reciprocable element to move said reciprocable element into said second position, means for making said cylinder-piston-assembly effective to move said reciprocable element into a third position, and means operable to mechanically move said reciprocable element into said second position.

12. In combination with a reciprocable element, a fluid operable cylinder-piston-assembly adapted to actuate said reciprocable element, actuating means for moving said reciprocable element into a first predetermined position, first fluid pressure responsive means adapted, in response to a first fluid pressure acting thereupon, to hold said reciprocable element in said first predetermined position independently of said actuating means, means associated with said reciprocable element for urging the latter into a second predetermined pressure, second fluid pressure responsive means adapted automatically in response to a second fluid pressure acting thereupon and higher than said first fluid pressure to make said first fluid pressure responsive means ineffective, thereby allowing said last mentioned means to move said reciprocable element into said second predetermined position, and means for making said cylinder-piston-assembly effective to move said reciprocable element into a third predetermined position.

GEORGE A. WALDIE.
